CLAIM

We claim, the ornamental design for a panel for intake
manifold, as shown and described.

DESCRIPTION

Cross-reference is made to U.S. Design patent application
Ser. No. 29/713,625, titled "Manifold," U.S. Design patent
application Ser. No. 29/713,626, titled "Manifold," U.S.
Design patent application Ser. No. 29/713,628, titled
"Throttle Body Adapter," all filed on Nov. 18, 2019 and all
of which are expressly incorporated herein by reference.

FIG. 1 is an upper perspective view of a panel for intake
manifold showing our new design;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1.
